MANDREL SUPPORT

Earl G. Hill, Pulaski, Va., assignor to Textile Appliance Corporation, New York, N. Y., a corporation of New York

Original application July 12, 1945, Serial No. 604,627. Divided and this application August 19, 1947, Serial No. 769,464

3 Claims. (Cl. 242—43)

1

This invention relates to machines for winding packages of yarn, thread, etc., and is concerned more particularly with novel means for use in a winding machine for supporting the mandrels for the tubes or cores, upon which the yarn is wound. The new mandrel supports are of simple, inexpensive construction, and the mandrels may be easily inserted in and removed from the supports. Also the supports occupy little space in a direction lengthwise of the mandrel supported thereby, so that, when the supports are employed in a machine having a plurality of winding units in a line, the units may be placed closer together than would be possible if certain prior supports were used.

The new mandrel support is intended primarily for use in winding machines of the type, in which the mandrel is rotated by a rotary member, such as a driven cork roll, in constant contact with the surface of the yarn package being produced, an example of such a machine being that disclosed in my co-pending application, Serial No. 604,627, filed July 12, 1945, now Patent No. 2,475,895, issued July 12, 1949 of which this application is a division. The supports are mounted at opposite ends of each cork roll and each support includes a standard having a slot in one side face. The slot extends transversely to the axis of the cork roll and downwardly therefrom at a low angle. The bottom of the slot and its upper end are closed and, at the lower end of the slot, there is an entrance opening into the slot through the top wall thereof. The support may be made by a casting operation and the supports, which are to lie between a pair of winding units in a multiple unit machine, may be combined into one, such a compound support having slots lying back to back with their openings facing in opposite directions.

For a better understanding of the invention reference may be had to the accompanying drawings, in which

Fig. 1 is a plan view of a portion of a winding machine equipped with the new supports;

Fig. 2 is a view of the machine in front elevation;

Fig. 3 is a sectional view through a single winding unit, on the line 3—3 of Fig. 4;

Fig. 4 is a sectional view on the line 4—4 of Fig. 3;

Fig. 5 is a view in perspective showing the upper part of one mandrel support; and

Fig. 6 is a sectional view on the line 6—6 of Fig. 1.

In the drawing, the mandrel supports of the

invention are illustrated in use in a drum winding machine of the construction disclosed in the co-pending application. Such a machine includes a supporting structure made up of vertical frame members 10 and longitudinal members 11 of suitable construction. A shaft 12 is mounted in bearings on the structure to extend lengthwise of the latter and the shaft is provided at intervals with conventional cork driving rolls 13. The shaft is continuously rotated by suitable means (not shown). A mandrel 14 is mounted for rotation opposite each cork roll 13 and, prior to the winding operation, a tube 15 is slipped over the mandrel. The mandrel is provided with gudgeons 16 at its ends and the gudgeons are inserted in the mandrel supports 17, 18.

The mandrel supports 17 are disposed at opposite ends of the machine and each such support includes a standard 19 mounted on the supporting structure at one side of shaft 12 and beyond the outer ends of the cork rolls 13 at the ends of the machine. At the upper end of its standard 19, each support 17 is formed with a slot 20 in its side face, the slot extending downwardly in a direction away from the shaft 12. The upper end of the slot lies in a horizontal plane through the shaft and is closed by a wall 21. The bottom of the slot is closed by a vertical wall 22 and, at the lower end of the slot, there is an entrance opening into the slot formed between the lower end of the top wall 23 of the slot and a vertical wall 24 rising from the lower wall 25 of the slot and extending upwardly above the top wall 23.

The mandrel supports 18 lie between the end supports 17 and opposite the spaces between adjacent cork rolls. Supports 18 are of the compound type and each such support includes a standard 26 formed at its upper end with a pair of slots separated by a common bottom wall 27, the slots opening laterally in opposite directions from that wall. The slots of support 18 extend downwardly in a direction away from the shaft 12 and have lower end walls similar to wall 24 and entrance openings through the upper walls of the slots at the lower ends thereof. The upper ends of the slots of support 18 are closed and lie in a horizontal plane through shaft 12.

In order to place a mandrel with a tube thereon in position in the supports, the gudgeons 16 of the mandrel are inserted through the entrance openings into the lower ends of the slots in a pair of mandrel supports at opposite ends of a cork roll. The mandrel and tube are then moved upwardly in the supports to bring the tube into contact with the cork roll 13. In the machine

illustrated, the mandrel is moved toward the cork roll by a frame, which comprises a plate 28 provided at its lower corners with brackets 29 pivotally attached at 30 to brackets 31 secured to the longitudinal frame members 11. At its upper end, the plate is provided with brackets 32 projecting toward the cork roll, and a roller 33 is mounted between brackets 32 in position to bear against the tube 15 on the mandrel or the package being wound on the tube. Roller 33 is spaced from the adjacent face of plate 28 and a thread guiding rod 34 is mounted in brackets 35 on the outer face of plate 28.

A traverse bar 36 is mounted in suitable guides (not shown) on top of the longitudinal member 11 to extend parallel to shaft 12 and the bar is reciprocated endwise, during the operation of the machine, by means (not shown). Opposite each cork roll, the traverse bar 36 carries a pair of spaced brackets 37 and an arm 38 is pivotally mounted in each pair of brackets 37. For this purpose, the arm is formed at its lower end with a loop encircling a pin 39 having coned ends, which are receivable in openings in the brackets. The axis, about which arm 38 swings, is coincidental with the axis, about which plate 28 swings, so that, as the plate swings outwardly, the arm 38 may swing with it and remain parallel thereto.

A lever 40 is pivoted at 41 on the arm 38 below the top thereof, the lever being of bell crank form and having a short horizontal leg and a long vertical leg. The short leg is provided with a roller 42 extending from the rear face of the lever and the vertical leg carries a thread guide 43, which extends upwardly between roller 33 and plate 28.

A guide plate 44 is pivotally mounted at 45 on the inner face of plate 28 and the guide plate has a longitudinal slot 46, in which travels roller 42 on lever 40. A cam plate 47 is attached to one of the brackets 30, in which the plate 28 is mounted, and extends outwardly at right angles to the plane of plate 28 and through an opening 48 therein. The cam is engaged by one end of the guide plate 44, and the guide plate is held in contact with the top surface of the cam by a spring 49 attached at one end to plate 28 and bearing at its free end in a slot in the upper edge of the portion of guide plate 44 encircling the pivot 45. Near its outer end, the cam is formed with a notch 50, into which the end of guide plate 44 may drop when the frame is swung outwardly sufficiently far from the package on the mandrel. In order to release the guide plate from notch 50, the plate is provided near one end with a pin 51, which extends through an opening 52 in plate 28. By raising the pin, the end of the guide plate may be released from the notch.

Each frame is urged to swing toward its cork roll by a spring 53 attached at one end to plate 28 and at its other end to a fixed part of the structure of the machine. The spring acts to cause roller 33 to contact with tube 15 on the mandrel or with the package being wound on the tube and the tube or package is thus held in contact with the cork roll 13 so that the mandrel is rotated by the roll. As the frame swings away from the cork roll during the growth of the package on the tube, roller 33 engages the thread guide 43 and this causes arm 38 and lever 40 to swing with the frame.

At the start of operation of the winding machine, each frame is swung away from its cork roll, until the guide plate 44 of the frame drops

into the notch in the associated cam 50. As the frame swings away from the cork roll, the mandrel gudgeons roll down the slots in the supports, until they strike the lower end walls 24 of the supports. The mandrel can be removed from its mounting and a tube slipped over it, after which the mandrel is placed back in position with its gudgeons in the slots in the supports and engaging the faces of the end walls 24 of the slots. When the guide plate 44 of the frame is released from the notch, the spring 53 swings the frame toward the cork roll and, in this movement of the frame, its roller 33 engages the tube 15 and moves the tube and mandrel upwardly, along the supports, until the tube makes contact with the cork roll 13. The thread 54 from the supply is then passed upwardly over guide bar 34, through the thread guide 43, and over roller 33 to the tube on the mandrel.

When the machine is started, the traverse bar 36 is reciprocated and moves each arm 38, each lever 40, and each thread guide 43 with it. As a lever 40 moves along the face of its plate 28, the engagement of the roller 42 on the lever in the slot 46 in guide plate 44 causes a backward rocking of lever 40 at each end of each stroke of the traverse bar. In such backward rocking of lever 40, its upper end moves in a direction opposite to that in which the lever as a whole is moving relative to its plate 28. The extent of such rocking movement of the lever depends on the inclination of the slot 46 in the guide 44 for that lever, and the inclination of the slot is determined by the shape of cam 47. As the package on the tube on a mandrel builds up, the axis of the mandrel moves away from its cork roll and the frame is moved outwardly. This causes the guide plate 44 on the frame to move along the surface of its cam 47, and, by properly forming the cam, the traverse of the thread guide lengthwise of its mandrel is progressively shortened, so that the package formed on the tube on the mandrel has tapered or coned ends.

When the winding of the package has been completed, the frame for the mandrel of the package is moved outwardly, until its guide plate 44 drops into the notch 50 on the cam. At that time, the gudgeons of the mandrel have rolled down in the slots in their supports and rest opposite the entrance openings into the slots and against the walls 24 at the ends of the slots. The mandrel with the full package thereon can then be moved, the package taken off the mandrel and replaced by an empty tube, and the mandrel gudgeons may then be put back into the lower ends of the slots. When the guide plate 44 of the frame is released from the notch, the frame swings toward the cork roll and its roller 33 moves the mandrel and tube upwardly along the supports, until the tube engages the cork roll. The insertion of a mandrel into the supports and its removal therefrom are thus simple operations, and, when a mandrel has been mounted in its supports, it is brought automatically into the desired relation with its cork roll by the action of the frame associated with that roll.

I claim:

1. In a winding machine having a drum rotating on a horizontal axis and a mandrel for a core on which a package is to be wound, the combination of a pair of members lying at one side of the drum and formed with slots in their opposed faces for receiving the ends of the mandrel, the slots lying parallel to each other and normal to the axis of the drum and extending downwardly

in a direction away from the drum at a small angle to the horizontal, the upper ends of the slots lying approximately in a horizontal plane through the axis of the drum and the lower ends of the slots being closed, entrance openings in the tops of the members leading into the slots near the lower ends thereof, and means for urging a mandrel having its ends in the slots in the members into contact with the drum, said means including a plate pivotally mounted between said members on an axis parallel to and at a lower level than the axis of the drum, spring means acting on the plate and tending to swing its upper end toward the drum, and a roller mounted on the plate for rotation on a horizontal axis near its upper end.

2. In a winding machine having a drum rotating on a horizontal axis and a mandrel for a core on which a package is to be wound, the combination of a pair of mandrel supports lying at one side of the drum and formed with slots in their opposed faces for receiving the ends of the mandrel, the slots lying parallel to each other and normal to the axis of the drum and having their ends closed, the upper ends of the slots lying approximately in a horizontal plane through the axis of the drum and the slots extending downwardly therefrom at a small angle to the horizontal, entrance openings in the tops of the supports leading into the slots near the lower ends thereof, a plate pivotally mounted on a horizontal axis below the level of the drum axis and lying between vertical planes through the supports, a spring connected to the plate and tending to swing it so that its upper end approaches the drum, and latch means for holding the plate outwardly from the drum beyond the lower ends of the slots.

3. In a winding machine having a drum rotating on a horizontal axis and a mandrel for a core on which a package is to be wound, the

combination of a pair of mandrel supports lying at one side of the drum and formed with slots in their opposed faces for receiving the ends of the mandrel, the slots lying parallel to each other and normal to the axis of the drum and having their ends closed, the upper ends of the slots lying approximately in a horizontal plane through the axis of the drum and the slots extending downwardly therefrom at a small angle to the horizontal, entrance openings in the tops of the supports leading into the slots near the lower ends thereof, a plate pivotally mounted on a horizontal axis below the level of the drum axis and lying between vertical planes through the supports, a roller mounted near the upper end of the plate on the side of the plate opposed to the drum for rotation on a horizontal axis, a spring connected to the plate and tending to swing it so that its upper end approaches the drum, and latch means for holding the plate outwardly from the drum beyond the lower ends of the slots.
